Frank D. Morris,

Richard Bowen,
his Attorney

UNITED STATES PATENT OFFICE.

FRANK D. MORRIS, OF CRESTON, IOWA.

ELECTRIC SWITCH APPARATUS.

1,185,123.

Specification of Letters Patent. Patented May 30, 1916.

Application filed October 18, 1913. Serial No. 795,986.

To all whom it may concern:

Be it known that I, FRANK D. MORRIS, a citizen of the United States, residing at Creston, in the county of Union and State 5 of Iowa, have invented certain new and useful Improvements in Electric Switch Apparatus, of which the following is a specification.

This invention relates to distributing 10 boards for electric current and the primary object thereof is to provide a single apparatus capable of operating two instruments, either singly or together; to reduce the number of parts and joints of such apparatus; to diminish the number of contact 15 surfaces; to economize in labor and material; and to improve generally the construction and arrangement of the several parts of the said apparatus.

20 A further object of the present invention contemplates the provision of an electric switch apparatus or distributing board wherein a plurality of switch levers are arranged and electrically connected in such a 25 novel and peculiar manner as to combine in a single organization means whereby two independent instruments may be operated at one and the same time or either independent of the other.

30 The above and additional objects are accomplished by such means as are illustrated in their preferred embodiment in the accompanying drawings, described in the following specification and then more particularly pointed out in the claims which 35 are appended hereto and form a part of this application.

In describing my invention in detail reference will be had to the accompanying 40 drawings wherein like characters denote like or corresponding parts throughout the several views, and in which:

Figure 1 is a top plan view of a switch board constructed in accordance with the 45 present invention; Fig. 2 is a side elevation of the same; and Fig. 3 is a section on the line 3—3 of Fig. 1.

Referring now to the drawings wherein is illustrated the preferred embodiment of 50 my invention the numeral 1 designates an insulating board or base to which the apparatus comprising the present invention is attached. Adjacent one end of the board 1, and fixedly secured thereto in any suitable 55 manner, I provide a substantially U-shaped plate member 2, the same being seated with-

in a cut out portion 3 of the said base, the extensions of the said member 2 extending vertically as at 4, one upon each side of the base 1. A binding post 5 is carried by the 60 said plate member 2, the said binding post being preferably seated within the cut out portion 3 as is illustrated to advantage in Fig. 2 of the drawings, thereby providing for the attachment of a positive conductor 65 to thereto.

A second or substantially U-shaped plate member 7 is arranged in spaced relation to the top of the base 1, the extensions of the said U-shaped member 7 being supported in 70 parallel spaced relation to the extensions 4 of the plate member above mentioned. A bridge plate 8 is secured to the top of the base 1, one extremity of the said bridge plate 8 projecting beyond the edge of the 75 said base, the projected portion supporting a binding post 9 to which the negative conductor 10 is attached. The plate member 7 is secured fixedly as at 11 to the bridge portion of the said member 8 directly over and in spaced relation to the plate member 2, no conductor of electricity however being provided therebetween.

Pivoted as at 12 to the extensions 4 of the plate member 2 and as at 13 to the extensions of the plate member 7, I provide a switch lever 14, the plate of each lever, (there being two) connecting respectively one extension of the plate member 2 with the adjacent extension of the plate member 7 as is 90 clearly indicated in Fig. 1 of the drawings.

Contact plates 15, of which there are four in the present instance, are disposed in the path of the switch levers 14, one contact plate being provided for each blade of the 95 said levers, the said contact plates being secured in any suitable manner upon the upper or outer face of the switch base 1.

A positive conductor 16 is connected to one of the contact plates 15, the said conductor 100 having associated therewith a fuse-plug 17 for an obvious purpose and terminating as at 18 where it is electrically connected to the binding post as shown. From the binding post 18 the conductor extends to the instrument to be electrically operated, the wire 19 being illustrated as a conducting medium. From the instrument (not shown) a return or negative wire 20 conveys the electric current to a binding post 21, the current being then conveyed through the negative wire 22, through a second fuse-plug 23,

and then to the contact plate 15 adjacent the contact plate aforesaid, the latter contact plate being disposed to receive the other switch plate of the one lever 14 now being 5 described thereby providing for the conducting of the current to the lower plate member 7, then to the bridge plate 8 and the negative conductor 10.

The other switch lever 14 electrically connects the plate members 2 and 7 in the same manner as that just described, thereby providing for the operation of a second or independent instrument (not shown) either independent of or together with the instrument first mentioned.

Having described fully the construction of the distributing board or switch apparatus, it now remains to set forth a little more fully the path of the electric current to and from the said apparatus. When it is desired that the two instruments be electrically connected to the distributing board, to be operated at one and the same time, both switch levers 14 are swung into contact with the plate member 15. The electric current enters the distributing board through the positive conductor 6 and the comparatively large plate member 2, the said plate member conveying the current to the outer blade of the switch levers 14 through the conductor 16, binding post 18 and wire 19 to the instrument acted upon the negative current re-entering to the distributing board through the wire 20, binding post 21, conductor 22 30 and the opposite blade of the levers 14 to the comparatively small plate member 7 where it is conveyed by the bridge plate 8 to the negative conductor 10. When it is desired that a single instrument should be operated, that is, one instrument independent of the other, one of the switch levers 14 is swung out of contact with the plate member 15 provided therefor thereby causing the electric current to enter the board 40 through the positive conductor 6 where it is conveyed to either of the switch plates, one of the said plates being in engagement with the contact plate 15 provided and thence to the instrument and back to the negative conductor 10 in the manner above set forth. By disconnecting both switch levers from the contact plate 15, it is apparent that both instruments are rendered inoperative.

From the above, taken in connection with 55 the accompanying drawings, it will be seen that two independent electrically operated instruments may be operated either singly or together; that the number of conductors for supplying the electric current to the said 60 switch apparatus is reduced to a minimum; and that the switch levers are so connected as to distribute the electric current from a single positive conductor in a manner neces-

sary to the operation of two independent instruments.

In reduction to practice, I have found that the form of my invention, illustrated in the drawings and referred to in the above description, as the preferred embodiment, is the most efficient and practical; yet realizing the the conditions concurrent with the adoption of my device will necessarily vary, I desire to emphasize the fact that various minor changes in details of construction, proportion and arrangement of parts may 70 be resorted to, when required, without sacrificing any of the advantages of my invention, as defined in the appended claims.

Having thus fully described my invention, what I claim as new and desire to secure by Letters Patent, is:—

1. An electric switch apparatus including an insulated base, a plate member mounted to fit a groove therefor formed in the under side of said base, extensions formed at the 85 terminals of said plate member to engage with and extend above the longitudinal sides of said base, a second plate member mounted upon the opposite side of said base, a plurality of switch levers, one blade of each 90 lever having connection with said plate members, and contact plates mounted on said base with which the levers engage, substantially as described.

2. An electric switch apparatus including 95 an insulated base, the said base having a cut out portion formed in the under face thereof, a substantially U-shaped plate member seated within the said cut out portion, the extensions of the said plate member extending vertically in parallel spaced relation, one upon each side of the said base, a plurality of switch levers, one blade of each lever being pivotally connected to the said plate member, contact plates carried by the 100 said base with which the said blades are disposed for engagement, a second substantially U-shaped comparatively small plate member supported upon the upper face of the 105 said base in spaced relation to the said first mentioned plate member, a bridge plate forming a support for the said last mentioned plate member, one blade of each of the said levers being pivotally connected to the said last mentioned plate member, and contact 110 plates carried by the said base with which the said last mentioned blades are disposed for engagement, as and for the purpose set forth.

In testimony whereof I affix my signature 120 in presence of two witnesses.

FRANK D. MORRIS.
